UNITED STATES PATENT OFFICE.

WILFORD JUDSON HAWKINS, OF MONTCLAIR, NEW JERSEY.

PROJECTILE-FUSE TIME-TRAIN RING.

1,233,466.

Specification of Letters Patent. Patented July 17, 1917.

Application filed May 7, 1917. Serial No. 167,035.

To all whom it may concern:

Be it known that I, WILFORD JUDSON HAWKINS, a citizen of the United States, residing at Montclair, county of Essex, and State of

5 New Jersey, have invented a new and useful Improvement in Projectile-Fuse Time-Train Rings, of which the following is a specification.

This invention relates to an improvement 10 in projectile fuse time train rings.

In the time train rings for dial type fuses used heretofore, it has been customary to provide powder grooves having parallel walls, the grooves being open to the rear of 15 the ring or toward the body of the projectile. The powder is inserted in the ring groove under heavy pressure. It has been found that after a time a tendency exists for the powder to become loose in the ring groove.

20 It has been further found that the jar of gun fire and projectile acceleration to which the powder is subjected tends to produce displacement, or disintegration, or both, of the powder in the ring groove. Such displacement or disintegration results in a 25 change in the time burning of the fuse which is at variance with that pre-determined. In the use of high velocity projectiles, this variable and uncertain burning—due to the 30 causes mentioned—is highly objectionable because a variation of a small fraction of a second in fuse burning results in a relatively large time range variation during projectile flight. And where, as in present practice, great accuracy is essential in such 35 mechanisms, this defect is a serious one. The main object of the present invention is to overcome this defect of projectile fuse time train rings in order that greater accuracy may be attained.

40 As before stated, the powder is inserted in the time train ring groove under heavy pressure, and it has been found that this pressure results in spreading the walls of 45 the grooves slightly. This spreading tends to increase the tendency of the powder to be displaced or disintegrated. Another object of the invention therefore is the production of a time train ring having converging retaining walls undercut to resist displacement and disintegration of the powder during gun fire and projectile acceleration, the converging inclination of said walls being in excess of any possible spreading of said 55 walls during powder loading, so that even if

the walls are spread slightly by the loading operation, they will still act to resist displacement and disintegration of the powder in the groove.

With these and other objects not specifically mentioned in view, the invention consists in certain parts and constructions which will be hereinafter fully described and then specifically set forth in the claims hereunto appended.

60 In the accompanying drawings, which form a part of this specification and in which like characters of reference indicate the same or like parts, Figure 1 is an inverted plan view of a projectile fuse time train ring constructed in accordance with the invention; Fig. 2 is a cross-sectional view taken on the line 2—2 in Fig. 1; and Figs. 3 and 4 are fragmentary views illustrating modified forms of grooves.

65 In carrying the invention into effect, there is provided a projectile fuse time train ring provided with a device for resisting displacement and disintegration of the powder carried thereby during gun fire and projectile acceleration. In the best construction, the ring is provided with a powder groove having undercut retaining walls which are converging, the converging inclination of said walls being in excess of any possible spreading of said walls during powder loading.

70 The device selected to illustrate the invention is but one of many possible concrete embodiments of the same, and the invention therefore is not to be restricted to the precise details of the structure shown and described.

75 Referring to the drawings, 5 indicates a projectile fuse time train ring generally of a well known character but provided with a powder groove 6 having a rounded bottom 7, an inner retaining wall 8, and an outer retaining wall 9, said walls being undercut and converging, as clearly shown in Fig. 2. As before stated, the loading of the powder 80 into the ring groove ordinarily results in a slight spreading of the walls of the groove. In the present device, the converging inclination of the walls 8 and 9 is therefore designed to be in excess of any possible spreading; or in other words, to still resist displacement and disintegration of the powder within the groove even when a slight spreading of the walls occurs. The ring is further 85 provided with a flash hole 10, the purpose 90

100 of which is to provide a vent for the gases evolved during the burning of the fuse.

105

110

of which is well understood in the art and needs no description.

During gun fire and projectile acceleration, there is of course a tendency of the powder within the groove to be set back toward the face of the time train ring mounted behind the one here shown, as in the old devices. It will be readily understood, however, that the converging retaining walls 8 and 9 resist and prevent this set back movement, and therefore prevent the objectionable displacement and disintegration formerly due to such set back movement together with its attendant time changing effect.

In the modification shown in Fig. 3, the inner and outer walls are parallel at 11 and 12, but undercut and converging at 13 and 14, while the bottom 15 of the groove is flat.

In the modification shown in Fig. 4, the inner wall 16 and the outer wall 17 are undercut and converging, while the bottom 18 of the groove is substantially flat but rounded slightly at its junction with the walls.

Other forms of grooves not shown but capable of effecting the desired result may of course be used in place of the preferred form shown in Figs. 1 and 2, or either of the modified forms shown in Figs. 3 and 4.

What is claimed is:

1. A projectile fuse time train ring provided with a powder groove open to the rear and having retaining walls undercut to resist displacement and disintegration of the powder during gun fire and projectile acceleration.

2. A projectile fuse time train ring provided with a powder groove open to the rear and having converging retaining walls undercut to resist displacement and disintegration of the powder during gun fire and projectile acceleration.

3. A projectile fuse time train ring provided with a powder groove open to the rear and having converging retaining walls undercut to resist displacement and disintegration of the powder during gun fire and projectile acceleration, the converging inclination of said walls being in excess of any possible spreading of said walls during powder loading.

4. A projectile fuse time train ring provided with a powder groove having a rounded bottom and retaining walls undercut to resist displacement and disintegration of the powder during gun fire and projectile acceleration.

In testimony whereof, I have signed my name to this specification.

WILFORD JUDSON HAWKINS.
